US00D347067S

United States Patent [19]

Shartle et al.

[11] Patent Number: Des. 347,067
[45] Date of Patent: ** May 17, 1994

[54] ANALYTICAL CARTRIDGE FOR TESTING
BIOLOGICAL FLUIDS

[75] Inventors: Robert Shartle, Livermore; William Aldrich, Redwood City, both of Calif.

[73] Assignee: Biotrack, Inc., Fremont, Calif.

[**] Term: 14 Years

[21] Appl. No.: 670,151

[22] Filed: Mar. 15, 1991

[52] U.S. Cl. D24/223; D24/225

[57] CLAIM

The ornamental design for an analytical cartridge for testing biological fluids, as shown and described.

DESCRIPTION

FIG. 1 is a perspective view of one embodiment of the analytical cartridge for testing biological fluids, showing our new design;

FIG. 2 is a perspective view of the opposite side of the embodiment shown in FIG. 1;

FIG. 3 is a perspective view of a second embodiment of FIG. 1;

FIG. 4 is a rear elevation view of the embodiment shown in FIG. 1;

FIG. 5 is a front elevation view of the embodiment shown in FIG. 1;

FIG. 6 is a top plan view of the embodiment shown in FIG. 1;

FIG. 7 is a bottom plan view of the embodiment shown in FIG. 1;

FIG. 8 is a right side elevation view of the embodiment shown in FIG. 1; and,

FIG. 9 is a left side elevation view of the embodiment shown in FIG. 1.

FIG. 1

FIG. 2

FIG. 3

FIG. 6

FIG. 4

FIG. 5

FIG. 7

FIG. 8

FIG. 9
